UNITED STATES PATENT OFFICE

162,805

BALL POINT PEN

Fred Ferber, Englewood, N. J., assignor to Ferber Corporation, Englewood, N. J., a corporation of New Jersey

Application February 3, 1950, Serial No. 7,687

Term of patent 14 years

(Cl. D74—17)

To all whom it may concern:

Be it known that I, Fred Ferber, a citizen of the United States and a resident of Englewood, in the county of Bergen and State of New Jersey, have invented a new, original, and ornamental Design for Ball Point Pen, of which the following is a specification, reference being had to the accompanying drawings, forming part thereof.

In the drawings:

Fig. 1 is a view in elevation of a ball point pen embodying the new design.

Fig. 2 is a similar view with the parts disposed in separated juxtaposition.

Fig. 3 is an enlarged top view thereof.

Fig. 4 is an enlarged bottom view of the same. The pen is characterized by a transparent bar-

rel and with the ink holder visible through said barrel and shown in Figs. 1 and 2 by two longitudinally extending parallel lines.

I claim:

The ornamental design for a ball point pen, substantially as shown and described.

FRED FERBER.
